UNITED STATES PATENT OFFICE.

DANIEL I. MURRAY, OF DAYTON, OHIO.

DESIGN FOR A SPOON.

SPECIFICATION forming part of Design No. 21,595, dated May 31, 1892.

Application filed April 7, 1892. Serial No. 428,235. Term of patent 3½ years.

To all whom it may concern:

Be it known that I, DANIEL I. MURRAY, a citizen of the United States, residing at Dayton, in the county of Montgomery and State of Ohio, have invented and produced a new and original Design for Spoons; and I do hereby declare the following to be a full, clear, and exact description of the same, reference being had to the accompanying drawing, forming a part thereof.

The figure is a view of the top surface of the spoon.

The handle of the spoon has repoussé ornamental work along its sinuous edges. The end of the handle is nearly elliptical in contour and an irregular scroll occupies the interior space. A shield is on the left and on the right is a rock. An eagle with spreading wings stands with one foot on said shield and the other on said rock. To the right of the

eagle is shown the rising sun. In the bowl of the spoon near its junction with the handle are two rows of stars, thirteen in number, corresponding to the original States. In the center is shown a hemisphere of the world 25 exhibiting the parallels and meridians, the American Continent, and part of Oceanica. On said hemisphere is mounted an eagle with spreading wings and within the talons of which is held a scroll. 30

What I claim is—

The design for a spoon herein shown and described.

In testimony whereof I affix my signature in presence of two witnesses.

DANIEL I. MURRAY.
